CLAIM

The ornamental design for a USB flash drives with holder, as shown and described.

DESCRIPTION

FIG. 1 is a perspective view of the USB flash drives with holder in accordance with my new design;

FIG. 2 is an exploded perspective view thereof;

FIG. 3 is a top plan view thereof;

FIG. 4 is a front elevation view thereof, wherein the rear side is a mirror image;

FIG. 5 is a right side elevation view thereof;

FIG. 6 is a left side elevation view thereof; and,

FIG. 7 is a bottom plan view thereof.

The broken lines showing of the gripping elements and recesses on the individual USB flash drives and the fastening fingers on the main body of the holder in FIGS. 1-4 are for illustrating environmental structure only and form no part of the claimed design.
